UNITED STATES PATENT OFFICE.

SAMUEL C. YEATON, OF NEW YORK, N. Y.

INNER-SEALED RECEPTACLE.

1,108,961.

Specification of Letters Patent.

Patented Sept. 1, 1914.

Application filed November 3, 1913. Serial No. 799,013.

To all whom it may concern:

Be it known that I, SAMUEL C. YEATON, a citizen of the United States, and resident of the borough of Brooklyn, county of Kings, city and State of New York, have invented certain new and useful Improvements in Inner-Sealed Receptacles, of which the following is a specification.

This invention relates to inner sealed receptacles, that is to say, receptacles wherein the seal is contained in the interior thereof, as for instance, in the type of glass bottles wherein the seal is contained in the interior of the neck as distinguished from the capped or crown sealed bottles wherein the seal fits over the top and around the outside of the mouth of the bottle.

More particularly, this invention relates to that class of inner sealed receptacles in which the seals may be applied and removed without the use of implements.

The object of the invention is the devising of an inner seal of the above type, which by its own resiliency may be brought to the locking and unlocking positions without permanently distorting it, thereby permitting of its repeated use.

Referring to the drawings, Figure 1 is a fragmental sectional view of a bottle neck and a seal about to be inserted therein. Fig. 2 is a fragmental sectional view of a bottle neck and a seal inserted therein in sealing position. Fig. 3 is a plan view of blank seals. Fig. 4 is a fragmental sectional view of a bottle neck and a seal inserted therein but in a position to be removed from the neck, and Fig. 5 is a fragmental sectional view of a bottle neck and a modified form of seal inserted therein in sealing position.

The bottle neck 1 is provided with a seat 2 formed within the interior thereof and an abutment 3 also formed within the interior above the seat. The usual pliable gasket *a* of cork, rubber, or other suitable material is placed upon the seat as shown in Figs. 1 and 2. There is nothing novel about the use of these gaskets and are not shown in Figs. 4 and 5 but it is understood that they are preferably used where liquids are contained within the receptacles but may not be needed in other instances, as for instance, where the receptacle contains solid material.

The seal is stamped from suitably resilient sheet metal and comprises a body portion 4 of preferably circular formation and a plu-

rality of locking fingers 5 projecting from the body portion. The fingers are turned upwardly as shown in Figs. 1 and 2 and one or more of them may be provided with extensions 6 for the purpose as will presently appear. Fig. 3 shows an economical manner of stamping the disks. Here two extended fingers 6 are shown, the extended portions being taken from the waste portion of metal between three adjacent seals. The body of the seal is formed with a suitable upward bulge, as shown in Figs. 1 and 2.

Where the gasket *a* is used it may be first inserted on the seat 2 or it may be permanently secured to the seal in any suitable and well known manner. The seal is inserted in the neck by hand or by any suitable machine. The portion of the neck forming the abutment 3 is of suitable diameter to permit the seal body 4 to pass but the fingers 5 are obliged to crowd inwardly somewhat to pass this portion and when within the neck spring outwardly to normal or nearly normal positions, thereby locking themselves beneath the abutment 3. Pressure may be applied to the body of the seal to produce a squeeze upon the gasket and the fingers may be forced into locking position if found necessary when a very tight closure is desired, as in the case of bottles containing liquids under pressure. The stock forming the abutment 3 may be rounded as shown or may converge upwardly so that the farther the fingers are forced outwardly the more pressure they will exert upon the seat. This also permits the fingers to assume slightly different relative positions to adapt themselves to slight irregularities of formation of the bottle or seal. This makes it feasible in many cases to form a tight seal without the use of a sealing machine.

To remove the seal, the bulged body portion is forced downward. This tends to decrease the angularity of the body portion and if the fingers were held rigid would change the angularity between them and the body portion. The metal is however sufficiently rigid at the bend between the body portion and fingers to prevent a change of angularity between them with the result that as the inclination of the bulge of the body portion changes it swings the fingers inwardly correspondingly until they are free from the abutment. The extensions 6 are bent over as shown in Figs. 1 and 2 and may be gripped to pick the seal out of the neck.

when the body portion has been suitably depressed.

Pressure actuated bulged portions upon seals are not, broadly considered, new. 5 They are found in the U. S. Letters Patent to Flanigan, Number 11,629, Mulvaney, Number 800,867 and Kaufman, Number 851,424. These patents relate to crown seals, in which different principles are involved requiring different constructions than could be utilized with inner seals.

Where sufficient pressure is applied to the bulged portion to force it past a straight or plane position it can be made to assume a 15 reverse curvature. This will result in holding the fingers in their unlocked positions. But to lock the bottle the bulge will have to be forced back to its first or upwardly bulged position. When it is desired to prevent the bulged portion from passing or quite reaching the plane, the fingers are suitably spaced so that they will come together as shown in Fig. 4 before the bulged portion 4' reaches the plane but not until 20 the fingers 5' have moved free from the abutment. The fingers in this closed position resist the further depression of the bulged portion.

Fig. 5 shows another way of preventing 30 the bulged portion from reaching the plane. Here a disk 7 is placed beneath the seal. The disk is given a less curvature than the bulged portion 4'' so that when the bulged portion is depressed it will strike the disk 35 but not until the fingers have moved free from the abutment.

This seal is well adapted for such wide mouthed bottles as the ordinary milk bottle. It has the advantage of having the bulged 40 portion protected within the neck of the bottle so that the bottles may be placed one upon the other without affecting the seal. In the case of the cap variety of seal above referred to, the bulge extends above the top 45 of the bottle and if subjected to a blow or sufficient pressure by bottles or other weights placed upon it, would depress, which might result in opening the seal. It is possible to make part of the fingers wider, 50 or stiffer, or spread farther outwardly than the remainder, for instance, the fingers on the right in Fig. 1 may be thus reinforced. This will produce a relative weakness of the fingers on the left-hand side. When the 55 bulged portion is depressed the weaker fingers move first and the seal may be freed by raising that side from the bottle.

Having thus described my invention I claim—

1. The combination with a receptacle having a seal seat formed on the interior thereof and an abutment on the interior and above the seat, of a seal detachably supported by the seat having a yieldable upwardly bulged portion and upstanding locking fingers projecting therefrom engaged by the said abutment and releasably responsive to the depression of said bulged portion whereby said fingers move inwardly to clear the abutment. 60

2. The combination with a receptacle having a seal seat formed on the interior thereof and an abutment on the interior and above the seat, of a seal detachably supported by the seat having a yieldable upwardly bulged portion and a plurality of spaced locking fingers projecting therefrom engaged by the said abutment and releasably responsive to the depression of said bulged portion whereby said fingers are 65 brought inwardly into contact with each other to clear the abutment and to resist the further depression of the bulged portion. 70

3. The combination with a receptacle having a seal seat formed on the interior thereof and an abutment on the interior and above the seat, of a seal detachably supported by the seat having a yieldable upwardly bulged portion and a plurality of spaced locking fingers projecting therefrom engaged by the said abutment and releasably responsive to the depression of said bulged portion whereby said fingers are 80 brought inwardly into contact with each other to clear the abutment and to resist the further depression of the bulged portion. 85

4. The combination with a receptacle having a seal seat formed on the interior thereof and an abutment on the interior and above the seat, of a seal detachably supported by the seat having a yieldable upwardly bulged portion and upstanding locking fingers projecting therefrom engaged at their extreme upper ends by the said abutment and releasably responsive to the depression of said bulged portion whereby said fingers move inwardly to clear the abutment. 90

This specification, signed and witnessed this 25th day of Oct. 1913.

SAMUEL C. YEATON.
